UNITED STATES PATENT OFFICE

1,932,559

BRANDING-IRON FURNACE

George H. Parsons, Upland, Calif.

Application December 2, 1929. Serial No. 411,031

4 Claims. (Cl. 126—226)

This invention relates to devices used for heating branding-irons.

One of the objects of this invention is to provide a furnace or heating place that can be transported conveniently to any place where branding is to be performed.

Another object is to provide such a furnace so designed that the branding irons can be handled without difficulty by reason of the fact that the heating medium is in a fully enclosed container or structure.

Another object is to provide such a furnace with a grate by which fresh heating means are preheated from the top so that the further advanced heating material is close to the grate and thereby close to any branding-iron placed into the furnace from the top side of such irons.

Another object is to provide such a furnace with a tiltable grate whereby preheated or pre-ignited material can be caused to drop into a lower heating chamber so as to heat an inserted branding-iron from below, the whole structure tending to heat an inserted iron from all sides without great efforts and for consecutive uses.

Another object is to provide means whereby heating material can be regulated and controlled from the outside of the furnace.

Other objects will appear from the following description and appended claims as well as from the accompanying drawing, in which—

Fig. 1 is a side elevation partly broken away to show inside parts of a furnace with a tiltable grate and with a branding-iron in a proper position to be heated according to this invention.

Fig. 2 is a front elevation of the furnace of Fig. 1, illustrating the wide but shallow front opening through which a desirable number of branding-irons can be inserted into the furnace and spread out over the heating material under the tilting grate.

Fig. 3 is a fragmentary detail illustration of the tiltable grate in tilted position.

Branding is customarily done in the open field or at least at places where there is no convenient means to heat the branding-irons properly, and quite generally the heating of the irons is performed over open fires, which, of course, is not at all comfortable or pleasant inasmuch as considerable heat is required for the heating of the irons so that at times it is difficult to approach the fire close enough to properly place or remove the irons.

The principal feature with respect to this invention is therefore to provide a furnace that protects the operator against the heat from the

furnace and still offers a suitably wide surface over which a desired number of irons can be spread out conveniently.

As illustrated, the furnace consists principally of the shell or housing 4, the lower grate 5 and the tiltable grate 6. The front side of the housing is provided with an opening 7 through which a branding-iron may be disposed in the furnace as indicated at 8.

To assure a proper and quick heating of the iron, the whole furnace is preferably designed so that the iron is surrounded by fire from all sides.

A quick and convenient handling of the irons, on the other hand, can not be assured if the heating material, such as coal or wood, is piled over the top of the irons.

With this in mind, to facilitate a handling in a desirable manner, the whole structure or device is designed so that the heating material can be caused to drop to a certain level below one grate upon a second grate, a slight evening or straightening or flattening out of such dropped heating material may, of course, be necessary from time to time, the whole arrangement being partly automatic to maintain a comparatively even fire.

The grate 6 is therefore preferably mounted swingably as at the pivot points indicated at 9 at or near the rear edge of the grate, while connecting links 10 are provided to support the front edge of the grate. A lever 11 is swingably mounted at 12 and pivotally engaged at 13 by means of short lever portions 14 to the links 10 and thereby to the grate 6 at the pivot points 15 at or near the front edge of the grate.

A shield 16 is provided on the front edge of the grate by which a certain amount of heating material is held on the grate and which also tends to protect the operator from the heat while handling branding irons.

This tilting grate can be moved to the position illustrated in Fig. 3 so that the heating material can be caused to drop from the grate up to a small remaining portion as indicated at 17, the larger portion of the heating material dropping over the rear edge 18 into the lower compartment of the furnace to be maintained at about the level indicated at 19 in Fig. 1.

At this level the larger body of the heating material is eventually flattened out from time to time in such a manner as to leave only a narrow space between the underside of the grate 6 and the top surface of the accumulated heating material at 19 in order to assure a heating

of an inserted branding iron from all sides in the possibly shortest time.

Inasmuch as a comparatively narrow opening is left between the edge 20 of the opening in the front side of the housing 4 and the lower front edge of the grate 6 a radiation of heat from the heating material in the furnace is reduced to a minimum so as to enable an operator to place the branding irons advantageously and remove them conveniently.

The whole device is mounted on legs 21 to provide room for a suitable draft through the lower grate 5.

A door 22 is provided in one of the sides of the housing through which fresh heating material can be added to the burning and already ignited material at 17 on the upper tiltable grate, to be dropped again at suitable intervals into the lower compartment as stated above.

20 The flue 23 serves to assure a proper draft through the whole furnace.

Having thus described my invention, I claim:

1. In a furnace for heating branding-irons and the like, a housing having an opening in one side through which an article may be inserted to be heated, the opening having a lower edge at a certain level above which the article is heated, a grate for holding a heating medium and mounted in the housing closely above said edge, and means below said edge for holding another heating medium up to said level so that the inserted article may be supported by said second-named body of heating medium and embedded therein closely below the first-named heating medium and said grate and visible through said opening.

2. In a furnace for heating branding-irons and the like, a housing having an opening in one side through which an article may be inserted to be heated at a level near the lower edge of the opening, a grate mounted in the housing closely above said edge for holding heating matter, and means also disposed in the housing below said edge for holding another heating matter up to said level so that the inserted article may be supported by said second-named body of heating matter and embedded therein closely below the first-named heating matter and below said grate

and visible through said opening, the said grate being swingably mounted for discharging a portion of its burning heating matter for replenishing the second-named heating matter up to said level.

3. In a furnace for heating branding-irons and the like, a housing having an opening in one side through which an article may be inserted to be heated at a level near the lower edge of the opening, a grate mounted in the housing closely above said edge for holding burning heating matter, means also disposed in the housing below said edge for holding another body of burning heating matter whereby an inserted article may be supported by said second-named body of heating matter and embedded therein closely below the first-named heating matter and below said grate and visible through said opening, the said grate being swingably mounted for discharging a portion of its burning heating matter at a time for replenishing the second-named heating matter up to said level, and a supply door in the housing above said grate for charging heating matter onto said grate.

4. In a furnace for heating branding-irons and the like, a housing having an opening in one side through which an article may be inserted to be heated at a level near the lower edge of the opening, a grate mounted in the housing closely above said edge for holding burning heating matter, means also disposed in the housing below said edge to hold another body of burning heating matter whereby the inserted article may be supported by said second-named body of heating matter and embedded therein closely below the first-named heating matter and below said grate and visible through said opening, the said grate being swingably mounted for discharging its burning heating matter and for replenishing the second-named heating matter up to said level, a supply door in the housing above said grate for charging heating matter onto said grate, and a shield on said grate along and above the swinging edge adjacent said opening and forming a part-closing means for the opening.
